ATTORNEY

UNITED STATES PATENT OFFICE

GEORGE MILLER, OF CLEVELAND, OHIO, ASSIGNOR TO MILLER WHOLESALE DRUG COMPANY, OF CLEVELAND, OHIO, A CORPORATION OF OHIO

NEBULIZER

Application filed February 10, 1930. Serial No. 427,085.

This invention relates to a device for nebulizing liquids such as medicinal liquids for inhalation.

The atomizers now in use are usually irregular in outline, and relatively bulky, so that they are inconvenient to carry about. Likewise, the nebulizing nozzle or siphon and air vent are so constructed that they are difficult to seal, and consequently the atomizer must be carried in some particular position to prevent the liquid from escaping and soiling the clothing. Again, difficulty is encountered in providing a satisfactory seal about the joint between the liquid receptacle and the head which carries the atomizer nozzle and air connection.

Therefore, it is an object of my invention to eliminate these inconveniences and defects, and to provide a very efficient nebulizer which is compact and regular in outline, so that it may be conveniently carried about.

Another object is to provide a collapsible atomizer, the parts of which may be telescoped within the bulb for protection from breakage, and for additional compactness.

Another object of my invention is to prevent the escape of liquid in the nebulizer by efficiently sealing the liquid in the nebulizer, and to exclude foreign material from the various parts of the nebulizer and to disinfect them when not in use.

A convenient form of my nebulizer is illustrated in the accompanying drawing, wherein Fig. 1 is a longitudinal sectional view illustrating the various parts of my invention and their relative positions when in operation, and Fig. 2 is an elevation illustrating the same parts and their relative positions when telescoped.

The embodiment of my invention illustrated in the drawing includes a liquid receptacle 1 telescopically mounted in a bulb 2, of rubber or other resilient material. The bulb 2 is provided with an air intake 3, preferably located at one end, and an intake valve 4, which operates to prevent escape of air through the intake 3, as the bulb is compressed, and to permit entrance of air as the bulb resumes its normal expanded position.

At the other end the bulb terminates in an annular neck 5 and a sloping shoulder 6. The receptacle 1 is of the same cross sectional shape as the annular neck 5, preferably circular. The receptacle shown is in the form of a cylinder having an outer diameter slightly larger than the inner diameter of the annular neck 5, so that when inserted in the bulb it is gripped tightly by the annular neck to form an air seal.

Toward one end of the receptacle it is enlarged to form a chamber 7, the outer surface of which is shaped so that it is substantially complementary to the inner surface of the sloping shoulder 6 of the bulb. This forms an additional seal to prevent escape of air between the receptacle and bulb, and also prevents the receptacle from being blown or forced out from the bulb as the bulb is compressed for compressing the air therein and in fact forms a larger sealing area between the bulb and receptacle and draws the bulb tightly about the receptacle when the bulb is compressed. Within the receptacle 1 is an air tube 8 preferably integral and axially aligned with the receptacle. At one end the air tube 8 communicates with the bulb 2 through a suitable opening 9 shown in the wall of the chamber 7. The other end of the air tube is formed into a nozzle 10, discharging within the receptacle 1 near an open end thereof.

A suitable siphon tube 11 is provided within this receptacle and so located that its discharge end 12 projects over and slightly above the mouth of the nozzle 10. The siphon tube may be supported by the walls of the receptacle, or by securing it to the air tube 8, as shown. The siphon tube 11 extends preferably parallel to the air tube 8 and has its intake near the bottom of the chamber 7 and immersed in the liquid to be atomized.

The portion of the receptacle that may be filled with liquid and yet merit sufficient atomization is limited only by the discharge opening of the nozzle 10, which for operation must project out of the liquid. The pressure of air forced into the air tube by compressing the bulb is transformed into a velocity by the nozzle 10, causing a relatively low pressure

at the discharge end of the siphon tube. This results in drawing the liquid up through the siphon tube 11 and discharging it into the relatively high velocity air stream from the 5 nozzle 10. Here it is minutely broken up and mixed with the air, forming a mist or nebulus which is driven out of the receptacle by the air stream. The receptacle 1 is formed near its discharge end with a neck portion 13 10 having an annular shoulder 14. The length of the receptacle measured from its shoulder to its farthest end is such that when the receptacle is telescoped into the bulb 2, as illustrated in Fig. 2, the annular shoulder rests 15 upon the upper surface of the annular neck 5. The far end of the receptacle is a short distance from the valve end of the bulb 2.

It is desirable to form the inner surface of the lower end of the bulb substantially complementary to the adjacent portion of the outer surface of the walls of the chamber 7, so that the receptacle will be supported at both ends when telescoped and out of use. The outer surface of the neck portion of the 25 receptacle beneath the shoulder 14 is tapered or sloped inwardly of the receptacle so that when the receptacle is telescoped in the bulb the annular neck 5 of the bulb grips about the tapered portion of the neck 13 adjacent to the shoulder 14 of the receptacle and the shoulder 14 engages the end of the neck 5 of the bulb. This grips the receptacle so that it will not slip into or out of the bulb when not in use.

30 35 It is desirable to make the annular neck 5 relatively long and with heavy walls, so that it will hold the receptacle axially aligned and centrally located in the bulb. The discharge end of the receptacle is the only opening through which the liquid can escape. This end may be effectively sealed by a cork or other suitable means.

Thus the siphon or air tube and the parts with which the mist or nebulus contacts as it 40 45 is blown out from the receptacle are washed by the liquid or enveloped in the vapor therefrom so that they are maintained in a disinfected condition. I have provided an efficient, sanitary and compact nebulizer which 50 55 is capable of economical quantity production, and which may be carried about conveniently by the user without danger of leakage of the liquid.

55 I claim:

1. A nebulizer including a bulb, an open end receptacle for liquid longitudinally movable in said bulb, means in said receptacle for atomizing a portion of the liquid consequent upon compression of said bulb and for 60 discharging the atomized liquid from the receptacle, and a tapered neck portion on said receptacle, a bead at the end of the tapered neck portion, a portion of said bulb being contractible about said tapered neck portion 65 70 75 80 85 90 95 100 105 110 115 120 125 130 135

receptacle against longitudinal movement by engaging said tapered portion and bead when the receptacle and bulb are moved relatively to dispose the receptacle within the bulb.

2. A nebulizer including a bulb open at one end, an open end receptacle for liquid extending into and longitudinally movable in said bulb, and means in said receptacle for atomizing a portion of the liquid and for discharging the liquid so atomized from the receptacle consequent upon compression of the bulb, said receptacle having an enlarged globular portion at the closed end, said bulb being shaped to present its inner wall area in intimate contact with the surface of said globular portion at all relative positions of the receptacle and bulb intermediate and extended and telescoped positions while the bulb is uncompressed and the bulb presenting a considerable area in sealing contact with the receptacle in the relatively extended position of the receptacle and bulb, the bulb and receptacle being adapted for increasing the sealing area when the bulb is compressed whereby an effective seal between the bulb and surface of the receptacle is provided at the beginning of and during the compressing operation.

In testimony whereof, I hereunto affix my signature.

GEORGE MILLER.
